CLAIM

The ornamental design for a golf club head, as shown and described.

DESCRIPTION

FIG. 1 is a perspective view of a golf club head, as viewed from above, the front and one side.

FIG. 2 is a front elevation view of a golf club head of FIG. 1.

FIG. 3 is a rear elevation view of the golf club head of FIG. 1.

FIG. 4 is a side elevation view of a toe side of the golf club head of FIG. 1.

FIG. 5 is a side elevation view of a heel side of the golf club head of FIG. 1.

FIG. 6 is a top plan view of the golf club head of FIG. 1; and, FIG. 7 is a bottom plan view of the golf club head of FIG. 1.

The broken lines in the drawings are for purposes of illustrating environmental structure as well as portions of the design that form no part of the present claimed design.

1 Claim, 5 Drawing Sheets
